COMPRESS

Application filed March 25, 1929. Serial No. 349,779.

The invention relates to compresses and has for one of its objects to so construct a compress that it may be alternatively used for compressing material to standard or high density. Another object is to construct the compress with an intermediate invertible platen, which may be secured to either of the relatively movable platens of the compress to cooperate with one in compressing the material to standard density and to cooperate with the other to compress the material to high density. A further object is to so construct the compress that the intermediate platen may be readily inverted. With these as well as other objects in view, the invention resides in the novel features as more fully hereinafter set forth.

In the drawings:

Figure 1 is a diagrammatic end elevation of a compress embodying my invention;

Figure 2 is a side elevation thereof;

Figures 3 and 4 are views similar to Figure 1, showing the compress in different stages of conversion.

A compress used for compressing material, such as cotton, to standard density differs from a compress for compressing material, such as cotton, to high density, where both have the same relative movement of platens by having each of its relatively movable platens of greater width and consequently greater area than the platen of the high density compress opposite the high density attachment. The compress for compressing material, such as cotton, to standard density has the same parts as the compress for compressing cotton to high density.

As shown, the compress has the upper and lower relatively movable platens 1 and 2, respectively, the upper platen being stationary and the lower platen being reciprocable toward and away from the upper platen and having a fixed stroke limit. The lower platen has a width and consequently an area less than that of the upper platen so that this lower platen may be reciprocated between the side platens 3 of the high density attachment when the compress is a high density compress. 4 is an intermediate platen having a face 5 of substantially the same width and

area as the lower face 6 of the upper platen 1 and opposed face 7 of substantially the same width and area as the upper face 8 of the lower platen. This intermediate platen is invertible and may be fixedly secured alternatively to the upper and lower platens by suitable means such as the bolts 9. As shown in Figure 1, the intermediate platen is fixedly secured to the lower platen to present its face 5 opposed to the lower face 6 of the upper platen. As shown in Figure 4 the invertible platen is fixedly secured to the upper platen to present its face 5 opposed to the upper face 8 of the lower platen. In the former instance the compress is a standard density compress, while in the latter instance the compress is a high density compress, the side platens 3 of the high density attachment clearing the face 5 of the intermediate platen when these side platens are in operative position.

To facilitate converting the compress from a standard density to a high density compress or vice versa, the intermediate platen 4 is provided at its opposite ends with the aligned holes 10, in which may be engaged the pins 11. Flexible members, such as the chains 12, are secured at their upper ends to the opposite ends of the upper platen 1 and at their lower ends to the pins 11, the lengths of these flexible members being such that when the pins 11 are connected to the intermediate platen the flexible members will suspend the intermediate platen from the upper platen at a height such that the intermediate platen may be swung about the pins, the lower platen at this time being sufficiently below the intermediate platen to provide the necessary clearance. As shown in Figures 1 and 2, the lower platen 2 carrying the intermediate platen 4 has been raised sufficiently to provide for inserting the pin 11 into the holes 10 in the intermediate platen. The bolts 9 having been removed, the lower platen is then lowered a sufficient distance to permit swinging of the intermediate platen about the pins 11 and inverting this intermediate platen, Figure 3 showing the parts during this inverting operation. A suitable blocking means 13 is then placed upon the

lower platen and the lower platen is then raised to raise the intermediate platen into contact with the upper platen, as shown in Figure 4, after which the bolts 9 are secured in place, the compress now being ready upon removal of the blocking means to operate as a high density compress.

With this construction, it will be seen that the compress may be used either for compressing material, such as cotton, to standard or high density. It will also be seen that the compress in either case has the same parts, which, however, are differently combined or arranged. It will be further seen that we have provided a simple method for converting the compress.

What we claim as our invention is:

1. A compress having relatively movable platens with opposed faces of different areas, and an intermediate invertible platen forming a permanent part of the assembly and having faces corresponding in areas to the areas of the faces of said relatively movable platens.

2. A compress having relatively movable upper and lower platens with lower and upper work faces respectively, said upper face having a greater area than said lower face, and an intermediate invertible platen with opposite faces corresponding in areas to the areas of said lower and upper faces and means for alternately securing said intermediate platen to said relatively movable platens.

3. A compress having relatively movable platens with opposed faces of different widths and an intermediate invertible platen forming a permanent part of the assembly and having faces corresponding in widths to the widths of the faces of said relatively movable platens.

4. A compress having relatively movable upper and lower platens with opposed faces of different widths, an intermediate invertible platen with faces corresponding in widths to the widths of the faces of said upper and lower platens, and means for temporarily suspending said intermediate platen from said upper platen, including a flexible member for connecting said intermediate platen to said upper platen.

5. A compress having relatively movable platens with opposed faces of different areas, an intermediate platen having a face corresponding in area to one of the faces aforesaid and means for alternately attaching said intermediate platen to the relatively movable platens aforesaid.

6. A compress having relatively movable platens with opposed faces, one of said faces having a width substantially greater than the width of the other face, and an intermediate platen having a face corresponding in width to the first-mentioned face and means for alternately attaching said intermediate

platens to the relatively movable platens aforesaid.

7. A compress having relatively movable platens with opposed faces of different widths and an intermediate platen having faces corresponding in width to the faces of said relatively movable platens and means for alternately attaching said intermediate platen to the latter platen.

8. A compress having relatively movable upper and lower platens with opposed faces of different widths, an intermediate invertible platen with faces corresponding in widths to the widths of the faces of said upper and lower platens, and means for temporarily supporting said intermediate platen from one of the aforesaid platens to permit inverting said intermediate platen.

9. A compress having relatively movable platens with opposed faces of different areas, an intermediate invertible platen having a face substantially corresponding in area to one of the faces aforesaid, and means for alternately securing the opposite face of said intermediate platen in engagement with the opposed faces aforesaid of the relatively movable platens.

In testimony whereof, we affix our signatures.

HAROLD L. HAINES.
